UNITED STATES PATENT OFFICE.

FERDINAND A. SCHÄTZKE, OF MILWAUKEE, WISCONSIN, ASSIGNOR TO FRENCH WAX
FIGURE COMPANY, OF MILWAUKEE, WISCONSIN, A CORPORATION OF WISCONSIN.

DISPLAY-FIGURE.

1,319,800.

Specification of Letters Patent. Patented Oct. 28, 1919.

Application filed May 11, 1918. Serial No. 233,997.

To all whom it may concern:

Be it known that I, FERDINAND A. SCHÄTZKE, a citizen of the United States, and resident of Milwaukee, Milwaukee county, Wisconsin, have invented new and useful Improvements in Display-Figures, of which the following is a description, reference being had to the accompanying drawings, which are a part of this specification.

10 This invention has for its object to provide a window display figure with a removable top piece permitting a change from one composition coiffure to another or to one provided with natural hair.

15 In the art of window display figures it has been found desirable to use a painted plastic composition instead of wax with a coiffure or other head ornament of the same material, but in order to permit of variation to suit the different costumes with which the figure is draped and in order that the figure may be provided with natural hair at times, it is the object of the present invention to provide the figure with a suitable socket-like arrangement on the head adapted to receive and support interchangeable top pieces fitting therewith along the hair line so as to have the joint hidden from view.

20 Another object of this invention is to perfect details of construction of a demountable interchangeable top piece of this type.

With the above and other objects in view the invention consists in the display figure as herein claimed and all equivalents.

25 Referring to the accompanying drawings in which like characters of reference indicate the same parts in the different views:

Figure 1 is a view of a display figure provided with a demountable interchangeable composition top piece in accordance with this invention;

Fig. 2 is a view of such top piece removed;

Fig. 3 is a view of a wax top piece for substitution on the same figure to provide it with a natural hair coiffure;

Fig. 4 is a view of a plastic head ornament for substitution on the same figure; and,

Fig. 5 is a rear view of the top piece receiving socket on the head of the figure.

In these drawings 10 indicates a display figure which may be of any suitable material, though it is preferably of the painted composition type, and 11 is the irregularly shaped socket formed on the head thereof

with its edges along the hair line. Embedded in the figure is a pipe section 12 forming a tubular guide inclined in a direction that will permit of a removable top piece 13 to move into or out of a seating position in 60 the socket without binding therewith. The seating surface of the top piece is in reverse counterpart of the surface of the socket so that it closely fits within the socket, an inclined tubular stem 14 embedded therein and 65 projecting therefrom serving to fit within the guide tube 12 to determine the line of movement required for applying or removing the top piece. The top piece is preferably provided with a rounded enlargement 70 15 back of the stem 14 which by fitting in the corresponding cavity 16 of the socket forms a supporting bearing for the top piece positioned approximately beneath the center of gravity of the top piece to assist the stem in 75 the support of the top piece. While the various top pieces shown in Figs. 2, 3 and 4 are alike so as to interchangeably fit the socket 11 of the figure they differ in that the top piece 13 in Fig. 2 is provided with a 80 composition coiffure while the top piece 13' of Fig. 3 though mainly composed of composition or plaster of Paris has a deep wax covering 17 in which is embedded natural hair 18 shown in dotted lines, and the top 85 piece 13'' shown in Fig. 4 constitutes a composition head ornament of any fanciful design.

With this invention a composition figure may be varied by changing the top piece so 90 as to have either a composition coiffure or a natural hair coiffure or any other head ornament, so as to change its appearance from time to time or to suit the costume displayed thereon. With either the natural hair or 95 the composition top pieces the parting line between the top piece and the walls of the socket 11 is hidden from view by the hair being made to slightly overlap such line as shown in Figs. 2 and 3.

I desire it to be understood that this invention is not limited to any specific form or arrangement of parts except in so far as such limitations are specified in the claims.

What I claim as new and desire to secure 105 by Letters Patent is:

1. A display figure having a socket in the head thereof with the walls of the socket approximately along the hair line of the head, removable interchangeable top pieces fitting 110

in said socket, and means for guiding said pieces into and out of the socket.

- 5 2. A display figure having a socket in the head thereof with the walls of the socket approximately along the hair line of the head, a guide tube embedded in the socket, and removable interchangeable top pieces fitting in said socket each provided with a projecting stem fitting within the guide tube.
- 10 3. A display figure having a socket formed in the head thereof with the walls of the socket approximately along the hair line of the head, an inclined guide tube embedded in the socket, removable interchangeable top pieces fitting in the socket and each provided with an inclined stem embedded therein and fitting within the guide tube, and rounded depending enlargements on the top pieces fitting in a corresponding cavity of the
- 15 4. A display figure having a socket formed in the head thereof with the walls of the socket approximately along the hair line of the head, and removable interchangeable top

pieces fitting in the socket and overlapping 25 the edges of the socket.

5. A display figure of composition material provided with a socket in the head thereof with the walls of the socket approximately along the hair line, and removable interchangeable top pieces of composition material and of natural hair fitting in the 30 socket.

6. A display figure of composition material having a socket formed in the head 35 thereof with the walls of the socket approximately along the hair line of the head, and removable interchangeable top pieces fitting in the socket, one top piece forming a 40 coiffure of composition material and another constituting a wax base with hair embedded therein.

In testimony whereof, I affix my signature, in presence of two witnesses.

FERDINAND A. SCHÄTZKE.
